INVENTOR:

Georges Robinet

BY *Georges Robinet*

ATTORNEY

UNITED STATES PATENT OFFICE.

GEORGES ROBINET, OF PARIS, FRANCE.

CONTAINER FOR DENTAL IMPRESSION OUTFITS.

Application filed November 22, 1924, Serial No. 751,596, and in France November 28, 1923.

The object of my invention is to provide a case or chest containing in a compact manner and, due to tight closure, protecting against dust, weather or temperature influences and generally against any detrimental contact the materials, tools, instruments, accessories and all utensils used by dental surgeons for taking plaster impressions.

In order to make my invention more clearly understood I have illustrated, as an example, an embodiment thereof in and by drawings appended hereto and wherein:

Figure 1 is a front view of the case opened to show the inside arrangements.

Figure 2 is a cross-sectional view of the case closed.

Figure 3 is a detail sectional part view showing more particularly the spatula holders.

20 In all the figures the same reference numbers denote the same parts.

I wish it to be understood that any modifications introduced not only as regards the material used for making the case or container proper, but also as regards the form of the piece of furniture, chest, box, glass case or any other constituting the said container can have nothing to do with the characteristics of my invention.

30 In the embodiment shown the container is in the form of a chest made of pressed sheet iron in two parts 1, 2 united together by hinges 3 and closing as hermetically as possible. The closing is ensured by means of a latch 4 with an outside handle 5 or by any other means.

Inside, in the upper portion of each of parts 1, 2 are set horizontal rails 6 bent at the end and intended to carry the impression holders 7. The rails 6 in part 1 will for instance carry the lower impression holders and those in part 2 the upper impression holders or vice versa.

A metal shelf arranged at 8 in part 1 under rails 6 carries the numbered trays 9; a flange running along the front of the said shelf preventing the trays from slipping out.

A drawer 10, of suitable size, sliding under the shelf 8, encloses the salt intended

to be mixed with the plaster to accelerate the hardening thereof.

Plaster is contained in a box 11 made of metal or of any other suitable material and the mouth of said box is closed by means of a 55 hermetic stopper fitted with a rubber joint. Said box rests on a sheet iron plate 12 provided with a front flange and with an aperture 13 permitting a hand to be passed through to lift the plaster box and release it 60 from the housing.

On the same plate 12 are located the rubber cups 14 in a suitable number.

Lastly, in the space existing between cups 14 and shelf 8 is arranged the spatula-holder. 65 The spatulas 15 kept in the oblique slots 16 of pieces 17 suitably cross-braced, can be readily grasped, pieces 17 being adapted to slide along rails 18 in order to bring the spatulas in front of shelf 8. 70

In the embodiment shown a mirror 19 is fitted on the outer face of part 2 of the case.

The method of arrangement hereinabove described is not absolute since obviously, for instance, the plaster box, the cups, the spatula-holder and the trays could be arranged in the upper portion of the case and the lower portion of the latter reserved for the impression-holders. 75

Instead of being of pressed sheet iron, the 80 case or container could be made of corner-irons connected by sheet-iron or any other plates.

The container may just as well be in the form of a piece of furniture, of a glass case 85 carried on legs or applied against a wall or in the form of a shelf of such size as will facilitate its being shifted or moved about with all the products and appliances contained therein.

Having now particularly ascertained and described the nature of my said invention as well as the manner in which the same is to be performed, I declare that what I claim is:

1. In a container for dental impression 95 outfits embodying a pair of hinged shells, a spatula rack, means projecting from the wall of one shell, means connecting the rack to the projecting means whereby the rack is movable outwardly and inwardly of the 100

shell, and inclined slots in the rack adapted for the reception of spatulas.

2. A spatula rack for a container for dental impression outfits embodying a pair of hinged shells, such rack comprising a pair of parallel, horizontal rails adapted to be fixed to the wall of one shell in spaced re-

lation to each other, and a member slidably fitted on each rail for movement outward and inward of said shell, said members being provided with pairs of oblique slots to receive the spatulas. 10

In testimony whereof I affix my signature.
GEORGES RÖBINET.
